UNITED STATES PATENT OFFICE.

LUCIEN BRÉGEAUT, OF PARIS, FRANCE.

GAS-PRODUCING APPARATUS.

Application filed January 4, 1927, Serial No. 158,977, and in France January 14, 1926.

The present invention relates to an improved apparatus for the production of gas from volatile liquids such as petrol, and is chiefly characterized in that it comprises a plurality of evaporating conduits which contain wicks immersed in the liquid to be gasified and which are connected with two conduits whereof one is supplied with air preferably under pressure by a suitable blower or air compressing device and the other serves as a main collecting gas conduit. 10

Further characteristics will be specified in the following description with reference to the appended drawings which show only by 15 way of example, a constructional form of gas producer in accordance with the invention.

Fig. 1 is a plan view of the apparatus, and Figs. 2 and 3 are the corresponding end views.

20 Fig. 4 is a view on a larger scale showing a section on the line A—A of Fig. 1.

In this construction, the apparatus comprises the copper tubes 1 which are disposed above a fuel recipient 2 and contain the wicks 25 3 immersed in the liquid in the said recipient. The end of each wick which is immersed in the liquid is surrounded by an impermeable sheath 4 which is connected with the corresponding tube 1 and extends to a point 30 closely adjacent the bottom of the recipient. The tubes 1 are lined with a layer of a special blotting paper 5 which furthers the evaporation of the liquid which impregnates the wicks 3 by capillarity.

35 The tubes are connected on one side with the air conveying conduit 6 into which air is insufflated by an electrically driven blower 7, and on the other side with a conduit 8 serving as a chamber for the gas which is 40 circulated thence into the working devices by means of a distributor 9.

By the use of my said gas producer, the proportion of the vapour of petrol or other fuel is the exact equivalent of the quantity 45 of gas employed, that is to say said proportion is automatically kept constant and the vapour is proportioned without the use of mechanical means, thus offering a marked advantage, since the proper regulation is 50 always maintained and the construction of the apparatus is much simplified.

A tube or pipe 10 provided with a cock 55 connects the conduit 6 with the conduit 8, and allows of regulating the quality of the gas produced, according to the different densities of petrol in use, or to the room

temperature. The air tube 10 is preferably placed in the position shown in the drawings, and forwardly of the first tube of the set of carbureting tubes 1. By more or less 60 opening the cock 11 of this tube, or even by completely closing it, I obtain a gas which is more or less rich, due to the mixture of a greater or less amount of pure air with the carbureted air in the conduit 8. 65

To obviate all cooling effect occasioned by the evaporation of the petrol, which cooling effect would be prejudicial to the carburation, the tubes 1 are made of copper or other good heat-conducting material, so that the 70 cooling will be counteracted by the surrounding air which maintains the tubes substantially at the room temperature.

It will be noted that by reason of the impermeable sheath 4 which surrounds the 75 wicks 3 to within a short distance from the bottom of the recipient 2, the wicks 3 are supplied solely by the lower layer of the liquid in the recipient, whereby the fuel proportion will be quite constant from the 80 first to the last part of the liquid fuel employed.

Obviously, the present invention is not limited to the constructional forms herein represented which are given solely by way 85 of example and are susceptible of various modifications without departing from the spirit of the invention.

Having now described my invention, what I claim as new and desire to secure by 90 Letters Patent is:

1. Gas producer utilizing a volatile fuel, said producer comprising a reservoir for said fuel, a number of separate evaporating conduits above said reservoir, tubes connecting separately each of said evaporating conduits to said reservoir, wicks within said tubes and said evaporating conduits, a layer of absorptive material lining the inside wall of said evaporating conduits, means for producing air under pressure, an air conveying conduit connecting said means to said evaporating conduits, means for delivering the gas produced to the points of utilization and a gas collecting conduit connecting said evaporating conduits to said delivering means. 95 100 105

2. Gas producer utilizing a volatile fuel, said producer comprising a reservoir for said fuel, a number of separate evaporating conduits above said reservoir and connected separately thereto, means for causing said 110

fuel to ascend by capillarity from said reservoir to said evaporating conduits and evaporate therein, means for producing air under pressure, means for conveying said air to said evaporating conduits, means for collecting the gas produced within said evaporating conduits, means for connecting directly said air conveying means to said gas collecting means, means for controlling the air circulation through said connecting means and means for delivering said gas to the points of utilization of same.

3. Gas producer utilizing a volatile fuel, said producer comprising a reservoir for 15 said fuel, a number of separate evaporating conduits above said reservoir, tubes connecting separately each of said evaporating conduits to said reservoir, wicks within said tubes and said evaporating conduits, a layer 20 of absorptive material lining the inside wall of said evaporating conduits, means for producing air under pressure, an air conveying conduit connecting said means to said evaporating conduits, means for delivering the gas produced to the points of 25 utilization, a gas collecting conduit connecting said evaporating conduits to said delivering means, a separate pipe connecting directly said air conveying conduit to said 30 gas collecting conduit, and a cock controlling the air circulation through said pipe.

4. Gas producer utilizing a volatile fuel, said producer comprising a reservoir for 35 said fuel, a number of separate evaporating conduits above said reservoir, tubes connecting separately each of said evaporating conduits to said reservoir and extending close to the bottom of the same, wicks within 40 said tubes and said evaporating conduits, means for producing air under pressure, an air conveying conduit connecting said means to said evaporating conduits, means for delivering the gas produced to the points of utilization and a gas collecting conduit con-

nected said evaporating conduits to said delivering means.

5. Gas producer utilizing a volatile fuel, comprising in combination: an evaporating conduit adapted to be longitudinally passed through by a flow of air, a fuel reservoir, a wick extending along said conduit and filling substantially the cross section of said conduit, one end of said wick being immersed in the fuel contained in said reservoir, and means for collecting the gas produced in said conduit.

6. Gas producer utilizing a volatile fuel, comprising in combination: an evaporating conduit adapted to be longitudinally passed through by a flow of air, a fuel reservoir, 60 two wicks having their ends in said conduit respectively turned toward the conduit inlet and outlet, said wicks filling substantially the cross-section of said conduit, the other ends of said wicks being immersed in the 65 fuel contained in said reservoir, and means for collecting the gas produced in said pipe.

7. Gas producer utilizing a volatile fuel, comprising in combination: an air collector, a number of identical evaporating conduits 70 opening at equally spaced points of and into said air collector, a fuel reservoir, wicks extending along said evaporating conduits respectively and filling substantially the whole cross-section thereof, one end of said wicks being immersed in the fuel contained in said reservoir, a gas collector, the opposite ends of said evaporating conduits opening at equally spaced points of and into said 75 gas collector, a compressed air inlet opening into said air collector adjacent one determined conduit, and a discharge pipe opening into said gas collector adjacent said determined conduit.

In testimony whereof I have signed my 85 name to this specification.

LUCIEN BRÉGEAUT.
